[57] **CLAIM**

The ornamental design for a housing for the demand regulator of a breathing apparatus, substantially as shown.

DESCRIPTION

FIG. 1 is a left side elevation of a housing for the demand regulator of a breathing apparatus, showing my new design;

FIG. 2 is a front elevation thereof;
FIG. 3 is a rear elevation thereof;
FIG. 4 is a right side elevation thereof;
FIG. 5 is a top plan view thereof;
FIG. 6 is a bottom elevation thereof; and
FIG. 7 is a perspective view thereof.

FIG. 1FIG. 2FIG. 3FIG. 4
